[57] CLAIM

The ornamental design for a data entry terminal for electronic computers, as shown.

DESCRIPTION

FIG. 1 is a top, front and right side perspective view of a data entry terminal for electronic computers showing my new design;

FIG. 2 is a right side elevational view thereof;

FIG. 3 is a left side elevational view thereof;

FIG. 4 is an inverted front elevational view thereof;

FIG. 5 is an inverted rear elevational view thereof;

FIG. 6 is a bottom plan view thereof, and

FIG. 7 is a top plan view thereof.
